UNITED STATES PATENT OFFICE.

ORA D. SHAW, OF PHILADELPHIA, PENNSYLVANIA.

CAP.

1,177,822.

Specification of Letters Patent.

Patented Apr. 4, 1916.

Application filed April 7, 1914. Serial No. 830,145.

To all whom it may concern:

Be it known that I, ORA D. SHAW, a citizen of the United States, residing in Philadelphia, in the county of Philadelphia and 5 State of Pennsylvania, have invented new and useful Improvements in Caps, of which the following is a specification.

The invention relates to headgear, and more particularly to the class of caps, commonly known as uniform caps used more especially by motormen, conductors, and other uniform men.

The primary object of the invention is the provision of a cap wherein the frame 15 or foundation thereof is made from a single piece of loosely interlaced mesh or fabricated cane strips which is cut on the bias and reinforced with a stiffening band extended over a portion of its area to sustain such 20 portion fixed or rigid to avoid expansion or contraction at the basal circumference of the crown of a cap, while the remaining portion is capable of being extended or contracted to permit the proper shaping of 25 the upper part of the said crown, yet the frame when completely constructed is rendered exceedingly light in weight without depreciating its strength, and at the same time assuring flexibility with permanency of 30 original shape of the article irrespective of service and use.

Another object of the invention is the provision of a cap wherein the frame thereof is neat and attractive in appearance, 35 durable, and also which can be manufactured at a minimum expense, as there is considerable saving of materials and labor in the production of the article.

A further object of the invention is the 40 provision of a cap wherein its frame is more susceptible of shaping with the least possible labor while making the same to give the individual and desired ornamental and attractive appearance to the finished 45 article, and also which will obviate the possibility of disfiguring the covering thereof should the same become stretched taut over the frame by reason of shrinkage 50 of the covering material after becoming wet.

A still further object of the invention is the provision of a cap wherein the frame is of novel form to give maximum service and to insure the required ventilation when the cap is worn, as well as to give comfort to 55 the wearer.

A still further object of the invention is to generally improve in all details the make-up of the frame and cap in its entirety.

Other objects will be in part obvious and 60 in part pointed out hereinafter.

The invention accordingly consists in the features of construction, combination of elements, and arrangement of parts as will be exemplified in the construction herein- 65 after set forth, and the scope of the application of which will be indicated in the following claim.

In the drawing:—Figure 1 is a vertical longitudinal sectional view through a cap 70 embodying the invention. Fig. 2 is a portion of the blank from which the frame is made. Fig. 3 is a perspective view of the frame.

Similar reference characters indicate corresponding parts throughout the several views in the drawing.

The cap herein illustrated is of the bell crown flat top variety, although the invention is not limited to use in a cap of this 80 particular type.

The frame or foundation for the cap herein shown is designated generally by A, and it supports and holds in shape the outer covering B of cloth. The lower edge of the 85 outer covering B is folded under the lower edge of the frame, and to which is connected the usual sweat band C which is stitched at its lower edge to the outer covering B, as usual. The visor D is held in place in the 90 usual way by the stitching of the same both to the covering and frame. These parts, with the exception of the frame may have any suitable or usual construction, and form no part of the present invention. 95

The frame A comprises a body or skeleton form made from loosely interlaced cane strips 5 and 6 respectively, the same being arranged in loose criss-cross fashion interwoven in the manner as shown to form a 100

single piece body, the same being cut on the bias into the desired widths so that the strips 5 and 6 will be disposed in diagonal relation with respect to each other throughout the extent of the body. By reason of the particular construction of the body it is rendered freely flexible so that it will always resume its proper shape even after it has been bent out of shape, and by the 10 making of the body from the strips of material and the particular character of interlacing thereof makes the construction extremely light. Of course the strips may be made of any other suitable material which 15 has the desired characteristics, but as heretofore stated, the use of cane material that is ordinarily used in forming the cane seats of chairs is preferred. The woven cane material is cut into bias strips substantially 20 three and three-quarter inches wide, and said strips are joined end to end by lapping one over the other and stitching together, thus forming a continuous roll or length of material out of which a section for the cap body is cut with no waste of the cane stock. 25

The body is cut in the form of a band having a length equal to the circumference of the cap and a width substantially equal to the height thereof.

30 Stitched or otherwise secured to the inner face of the body to extend over substantially one-half of its width and throughout the length thereof is a reinforcing band 7, which is made from suitable material, such 35 as a piece of linen fabric stiffened by sizing applied thereto, which when united to the body sustains the basal circumferential portion of the frame fixed or rigid to prevent expansion or contraction thereof, while the 40 remaining portion of the body is free so that by stretching of such portion the upper part of the body can be expanded, or on compressing the free upper portion of the body the same can be contracted, thereby 45 enabling the proper shaping of the frame, after which a wire 8 is stitched or otherwise secured to the uppermost ends of the strips 5 and 6, which holds the body thus shaped for constructing the frame of the cap. It 50 is obviously within the scope of my invention to cut the interlaced fabric or mesh into strips substantially two inches in width and fastening to the upper edge of the basal band 7, but the preferred width is represented by the height of the cap. It is of 55 course to be understood that prior to the shaping of the body at the uppermost portion thereof the same is bent into ring-like form and the ends of the body are joined 60 together in any suitable manner, that is to say, the blank thus made is formed into circular shape by bringing the ends 9 and 10 thereof together and fastening them to each other in any desirable manner either by

stitches or a binding tape. The reinforcing 65 band 7 and the wire 8 when fastened to the body will sustain or hold the strips 5 and 6 at equi-distances apart to give uniformity to the make-up of the interlaced fabric or mesh. Any desired contour can be quickly 70 established by merely lengthening the wire 8 to produce an extreme bell shape or shortening said wire to form a flaring crown of less degree, and should an irregular shape 75 be desired, as for example, bell effect at 80 sides and back but straight front, it is produced by making the width of the body band less in front than at the sides and back. Thus, in constructing the fabric or mesh as hereinbefore described it is unnecessary to 85 remove any of the strips in constructing the said band and thereby avoiding any waste of material, and at the same time arriving at lightness of weight of the frame. A stretching of the body, by pulling on the 90 same at intervals, of the upper portion thereof uncovered by the reinforcing band 7 causes the expanding of such portion, and thereby enables the desired shape to be had.

The frame thus made is put into the cap 95 in the usual way and the cover B and sweat band C sewed in place. The cane material is very resilient and will resume its proper shape even after it had been disturbed by a blow or otherwise.

It will be apparent that the cap will insure proper ventilation to the head of the wearer when constructed in a manner as hereinbefore set forth, and also that its original shape will be permanently preserved. The frame will be materially reinforced or strengthened by reason of the diagonal disposition of the strips 5 and 6, or in other words, the bias characteristic of the body thereof. 105

It will be noted that the frame is made from a single piece and that the shape of the structure is produced by the spreading of interlaced cane strips fastened to the wire 8, thereby obviating the necessity of constructing it by the use of a number of curved or other shaped sections, and in this manner the frame is unbroken around the circumference of the cap both at the basal portion and at the tip or upper portion of the crown. 110

By reason of the lay of the strips 5 and 6 and the loose woven character thereof should the cover become stretched taut by shrinkage of the same after wetting over the frame 120 it will not cause the disfiguring of the cap as the cover will lie smooth and free from wrinkles or ridges.

What is claimed is:—

In a cap, a frame having a body formed 125 from loosely interlaced resilient strips, arranged in criss-cross fashion, with the said strips disposed diagonally with respect to

each other and gradually diverging from the bottom to the top of the body, whereby the latter is flared toward the said top thereof, the edges of the body being cut on 5 the bias, a stiffened band joined to and overlying substantially one-half of the width of the body, the upper remaining free portion of the body being expanded, and a wire

connected to the edge of the expanded part of the body.

In testimony whereof, I affix my signature in presence of two witnesses.

ORA D. SHAW.
